Primary Examiner — Mitchell I. Siegel(74) Attorney, Agent, or Firm — Randy K. Chang(57) CLAIM

The ornamental design for a golf ball marker, as shown and described.

DESCRIPTION

FIG. 1 is a perspective view of my new design for a golf ball marker;

FIG. 2 is a side view thereof;

FIG. 3 is a top view thereof;

FIG. 4 is a another side view thereof;

FIG. 5 is a front view thereof;

FIG. 6 is a bottom view thereof; and,

FIG. 7 is a rear view thereof.

The portion of the golf ball marker shown in phantom are for illustrative purposes only and do not form any portion of the claimed design.
